IGNITER-COMPOUNDER FOR INTERNAL COMBUSTION ENGINES

Francis M. Brooke, Bryn Mawr, Pa.

Application April 4, 1932, Serial No. 603,113

17 Claims. (Cl. 123—143)

My invention relates to the method of developing power in an internal combustion engine, by new methods of preparing or delivering explosive gases to the internal combustion engine for the purpose of ignition.

The object of the invention is as follows: To give a flexibility or a wide range of piston velocity in an internal combustion engine, using motor fuel oil with a low flash point. This obtains the same usefulness as a modern high speed internal combustion engine using a high grade gasoline or expensive high test motor fuels, but with the advantage of reducing the cost to the extent of ninety-one (91) per cent or more to that of motor fuel oil, by my invention. That is when the primary cylinder is designed at its average inlet pressure to explode ten (10) per cent of the volume of gas that the secondary cylinder at its average inlet pressure is designed to explode. In large engines, for ignition purposes only, the igniter can be relatively much smaller so that possibly only two or three per cent expensive high grade gasoline need be used for ignition purposes.

When it is desired to intensify the ratio of power to weight in smaller engines, the primary cylinder can be made larger and the ratio of inlet pressure materially increased, in which case additional power is obtainable with increased consumption of the more expensive gasoline. A compromise, however, may be reached by charging the primary cylinder not only with a moderate amount of high grade gasoline to increase the flash point for the electric spark, but also with air that has already been mixed with fuel oil, for the secondary cylinder. The effect of this will be a longer burning of the charge with excess air in the primary cylinder when it comes in contact with the gas in the secondary cylinder. It is possible that actually increased power may be so obtained with economy up to the point of a notable weakening in the efficiency of the electrical ignition.

My invention reduces the danger of conflagration by the fact that ninety-one (91) percent or more of the fuel that is carried for the engine will be of the low flash point and lower point of ignition fuel oil than that of the highly volatile gasoline or benzol preparations. In the process of obtaining the above there is a primary and a secondary explosion and compounding. This double explosion cycle facilitates the introduction to the cylinder, containing the piston, a greater volume of gas than has been previously utilized at the time of ignition. It will also give a high pressure at the time of the secondary ex-

plosion, due to the primary explosion and has eliminated the excessive compression pressure by the piston utilized in the Diesel engine to facilitate the explosion of motor fuel oil. Not only is the mean effective pressure less reduced by the ordinary excessive pressure of the compression stroke, but in addition the lower piston compression will make a smoother running and infinitely more flexible engine, provided, of course, that the charge can be successfully ignited, which is accomplished by my invention.

As a larger number of cubic inches of gas is forced into the piston chamber than in an ordinary internal combustion engine cylinder of the same given size, by my method, there is more potential energy or power. As there is an increase in power or efficiency in explosion somewhat proportional to the compression of these gases, prior to or at the time of the explosion, this efficiency is obtained in my contrivance by the primary explosion in the ignition chamber or igniter which exerts the pressure from explosion in the secondary cylinder, or piston chamber, as it simultaneously ignites the motor fuel in that chamber. This is at the time when the piston is virtually at the top of the stroke, or cylinder, so that the effort in creating the greatest part of the compression is supported by a primary explosion, not by the mechanical energy of compression previously developed by the engine, thus saving motor power.

It is, therefore, reasonable to believe that the engine will develop more power, per cubic inch of piston displacement. It possibly may show a greater efficiency in fuel consumed, and would seem to assuredly show a considerably lower cost per horse power developed, than that of other internal combustion engines, with anything like as great a range of flexibility in piston velocity.

Referring to the drawings:—

Figure 1 is a vertical cross section of the engine. Figure 2 is a vertical cross section of the cap 2 at the top of the engine, which holds movable parts in position.

Figure 3 is a plan of the cap 2.

Figure 4 is a vertical cross section of the water cooled primary combustion chamber 4.

Figure 5 is the plan of combustion chamber 4.

Figure 6 is a vertical cross section of the rotary sleeve valve for the primary chamber 4. This valve is comprehensively designated as 3.

Figure 7 is a plan of 3.

Figure 8 is a vertical elevation of 3.

Figure 9 is a cross section of 4 taken on the angle as designated by the plane ab in Figure 4.

showing the valve parts in 4, in relation to those of 3.

Figure 10 are the strips or rods used to control the position of 4.

5 Figure 11 is a longitudinal elevation from the left side of the engine in which part of the casing has been cut out to show, in cross section, certain essential parts, not shown in Figure 1.

10 Figure 12 is an elevation from the left side of the pump chamber showing an equalizing chamber in which compressed air or gas is stored.

Figure 13 is a rear vertical cross section of the pump showing slide actuated by the crank shaft driving connecting rod and piston.

15 Figure 14 is the sliding control 5 of the valve drive shaft, 41, with worm gears, 42, which actuate the sliding valves. The sliding control makes it possible to change the slide valve, 3, during operation, as may be desired.

20 A detailed description of the drawings are as follows:—

Figure 1 shows a cross section of the internal combustion engine of the ordinary L head type, that is, the inlet and the exhaust poppet valves 25 are on the same side. However, it has a super-structure 4 on the top that consists of a water cooled cylinder or combustion chamber, as shown in detail in cross section in Figure 2.

In the latter primary cylinder 4 or combustion chamber is located sleeve valve 3 shown in detail in Figures 6, 7 and 8. 3 is held in place by a cap, 2, shown in Figures 2 and 3, which is bolted on the head of the secondary cylinder, 39, which is fitted with piston 40.

35 It may be noted that there is a channel opening 24, from the top of the poppet valves of cylinder, 39, leading up to opening 23, which is opposite port 21 of 4.

In like manner, manifold inlet, 30, carries an explosive mixture of a high flash point, high grade gasoline preparation, to opening 22, opposite inlet port 20 of Figure 4.

40 Sleeve valve 3, (see Figure 6) has a solid base (see Figure 7) with gear teeth 26 on the perimeter. Referring to Figure 11, it may be noted that the rotations of shaft 41, revolve the worm drives 42, which are meshed with 7 and continuously rotate the sleeve valves 3, in one direction. This combustion chamber and the driving apparatus for its sleeve valve are shown and described in greater detail in my Patent Number 1,938,686 issued December 12, 1933. The opening 50 25, in sleeve valve 3 when it comes opposite to 20, permits a charge of explosive vapor to enter the primary explosive chamber 4.

55 The above charge is ignited by spark plug 15 by a distributor (not shown) and synchronized with control arm 29 of Figure 10. The charge, very shortly after being ignited, exhausts through port 21 of 4, through 23, into channel 24 and ignites the gases that have been compressed from and in channel 38, of Figure 1, by the upstroke of piston 40.

60 As sleeve valve 3 rotates further around, clockwise, port 21, becomes closed and the opening 25B, from auxiliary exhaust of sleeve valve 3 (see Figure 8), comes opposite to port 12, Figure 4. This reduces the pressure in 4 to atmospheric pressure as the gases exhaust through auxiliary exhaust pipe 43b. Auxiliary exhaust port 12 is still partially open when 25 again comes opposite 70 20, allowing a fresh charge into 4. This facilitates scavenging chambers 4 and also to virtually fill 4, with fresh gas without working against back pressure. 25b, auxiliary exhaust, passes 12, how-

ever, before 25 has become fully opposite 20, so that a combustion charge from 22 has ample time to build up a compression pressure before the slide valve is closed and ignited at the desired time by spark plug 15.

5 By referring to Figure 9, the action of this rotating valve and the various ports are evident. Figure 9, is taken through 4 on the angle ab, so that 25b is in a higher horizontal plane than 20 or 21, thus 25 never comes before 12, as does 10 25b; nor does 25b come before 20 or 21.

It may be noted that 22 and 23, Figure 1, horizontally are larger openings than 20 and 21. This is to control the time of ignition by control arm 29, in Figure 10, by pulling it either forward or backward, which slides one member of Figure 10 forward and the other correspondingly in the opposite direction, due to cross members 28, which are fastened by bolts 27. As these slides or strips 10, are fastened to pipes 16 in movable joints 17, (see Figure 4), this primary combustion chamber 4 can be rotated back and forth at will in an angle of approximately 120 degrees. In this way the relative position of ports 20 and 21, with regard to the position of piston 40, can 25 be regulated. If it is also desired, the size of the channel openings can be controlled by partially closing 20 and 21, when they have partially passed the limit of opening 22 and 23 if it is found desirable to have smaller ports.

30 As the electrical distributor is likewise synchronized with control arm 29, the timing of the explosion, relative to piston 40, can be easily arranged. Furthermore, a quadrant for a set adjustment can be arranged with 29, so as to set 35 most accurately the timing of the spark.

In addition sleeve valve 3 likewise can be advanced or retarded by the adjusting mechanism 5 (see Figure 14). As this is pushed horizontally along 41, when the engine is stopped, shaft 40 41 is rotated in one direction or another, dependent upon the direction in which 5 is pulled or pushed. Therefore, as the worm drive 42 revolves with shaft 41, sleeve valve 3 is either advanced or retarded and retains the set position in which 5 is left. It may be noted, however, that 5 is so designed that when the engine is running at any speed it still can be operated so that sleeve valve 3 can be so retarded or advanced. Incidentally, it can be moved with less 50 effort when the engine is running.

The combustion chamber 4 can be advanced or retarded also while the engine is running. Therefore, very complete flexibility of ignition timing, with regard to piston 40, can be arranged 55 by the combination of a perfect adjustment of the three adjustable parts, 3 and 4 and the electric distributor.

It may be noted that with a set adjustment of either 4 or 3 quite possibly sufficient variation 60 and flexibility in the time of ignition of the gases in secondary cylinder 39 may be arranged in each case. Then the engine may be materially simplified, particularly if 4 is made not independent but an integral part of the casting of cylinder 65 39, in which case water pipes 16, with flexible rubber hoses 63 can be dispensed with, the water jackets of 39 being made to include 4.

When the gases compressed in 24 and 38, by the compression stroke of piston 40, are ignited 70 by the exhausting of the primary explosion from 4, through 23, the effective pressure is developed in secondary cylinder 39, acting on piston 40. The gases in cylinder 39 have been developed from fuel oil because; first, of its relative cheap- 75

ness; second, because of its safety from fire where it is carried in storage and bulk, due to its low flash point; and third because of the high calorific value of the heavier oils. It is evident that such gases are not ignitable by an electric spark, because it is not sufficiently volatile and has too low a flash point. In previous experience this has been overcome by exceedingly high pressure from the piston on the compression stroke, the engine being designed to have very small clearance in ratio to the piston volume swept through.

There have been two practical limitations because of this latter method; the first, that as soon as the gases are compressed to a pressure above the ignition point, they will ignite, and it is impossible either to delay or advance this point and unless this corresponding point of temperature from compression pressure is not reached, there will be no explosion. Thus flexibility is impossible. The second consideration of difficulty is obtaining the smoothest running engine, because of the very high compression. In the new method being described, it is evident there is virtually an unlimited range of timing the ignition from the primary chamber. Therefore, the motor fuel gases in secondary cylinder 39 can be ignited at any reasonable point as piston 40 approximately reaches the top of its stroke or descends therefrom. Thus the maximum amount of flexibility is obtained by my invention.

It may be noted that by the burning gases coming from 4 into 39, through 24, a temperature very far above the ignition point of the motor fuel gases in 39 is obtained, also a great and increasing pressure. Thus not only the necessary temperature for ignition is developed, but also a high compression at the time of ignition, which makes efficiency, but this efficiency is obtained without the loss of effort due to piston compression against high back pressure. In addition there has been developed a great and increasing pressure against the piston; when effective.

It is also obvious that a larger volume of explosive gases exerts effective pressure on piston 40 than would be possible without primary combustion chamber 4. As the total volume of burned gases is equivalent to the sum of the gases contained in cylinder 39, plus that in cylinder 4, the latter would be true if the gases in 4 were but at atmospheric pressure and in 39 slightly below atmospheric pressure, when piston 40 is at the bottom of the stroke. This, however, is greatly intensified due to the fact that the gas in cylinder 4 is put under pressure and compounded before ignition so that it is very considerably above atmospheric pressure.

When the compounding feature is not desired a greater number of cylinders 4 can be attached to the compression pump and the pressure from the pump equalized by the storage equalizing chamber 45, Figure 13. If it is desired to maintain reasonably high pressure in primary cylinder 4, such cylinders can be made smaller.

It may also be noted that if it is desired, the compression pump can be eliminated altogether, the pressure developed in combustion chamber 4, coming entirely from a blower. In the latter case while all the advantages of ignition remain, the advantages of increased power of compounding are reduced.

As it is inevitable that primary combustion chamber 4 has the two effects of ignition regulation and compounding, they can be apportionately increased or decreased as the desire varies,

between the cost of fuel and the desirability of the amount of power developed in relation to the weight or size of the engine.

To trace back the development of the pressures and the mixing of the fuels (see Figure 5 11). Blower blades 46 are rotated by a shaft 47, which is driven by chain, 48, which in turn is driven by crank shaft 49. This develops a very strong pressure of air inside casing 50.

Such blower may have the dual purpose of 10 being used as a fan to cool the radiator. Small trap doors or inlet valves 51, with the blower housing 50, are kept closed by light springs when the automatic radiator shutter is open. When it closes the supply of air is not cut off as these 15 automatic inlet valves open under increased suction.

Fuel oil or other fuel is induced under pressure through pipe 53, through support 54 for the blades 46 and this fuel, is carried through the whirling 20 pipes, 59 to nozzles 60. This spray with the air from the blower is carried through manifold inlet 30 to primary cylinder 4 and through 32 to secondary cylinder 39. By using a shorter spray nozzle with jets at 61 and a guard extension in a 25 circle concentric to shaft 47, its perimeter being tangent to the part of manifold 30, nearest shaft 47, designated by 98, permits the driving of virtually pure air through 30 and air mixed with fuel oil through 32 to 39, giving an alternative. The 30 advantages and reasons for each of the latter two arrangements have been discussed in the first part of the specification.

With set valve 6 in place the currents from the blower pass into pump inlet pipe 62, through inlet valves 63, (see Figures 12 and 13) and as the plunger 64, of the pump, makes its double action stroke, automatic exhaust valves 65 automatically open into pump exhaust 66, to manifold inlet 30. The latter pipe has been made of larger diameter so as to 40 include carburetor 69 which is supplied with gasoline.

The air pump is operated by the crank shaft 49, has a bearing 77, which rides in a cage 78, horizontally back and forth in slide 79, which reciprocates up and down between guides 80. As 79 goes up and down it so forces connecting rod 81, which passes through stuffing box 82, and forces double acting piston 64 up and down. Valves 63 are automatic inlet valves which are simply held in 50 position by a light spring so that when there is suction they open. In like manner the exhaust valves 65 are similarly constructed, only they raise on the other side of the valve seat so when there is suction they are closed additionally tight and 55 when there is pressure they open against the light spring.

The cooling of the engine is arranged by pump 92, which forces the water from radiator 93, which is equipped with automatic radiator shutter 94, 60 through inlet pipe 34, see Figure 11 and Figure 1, through 36 to cylinder 39. In a like manner the water is returned through connection 35 to pipe 33, back to radiator 93.

The primary cylinder 4 is cooled by water pipes 65 34b, which receive their supply from pipe 34 and by flexible hose connections, connected to pipe 16; the water passing through opening 18. The water after circulating through 4 comes out passage 18b, through pipe 16b, through pipe 33b, into pipe 33, through which it is taken to the radiator.

The engine is supported on basis 96.

Shaft 41 is driven by gear wheel 91 which is driven by chain 98, which receives its force from 75

gear 99 on crank shaft. The same chain drives the blower as it laps over gear 100. (See Figure 11.)

Shaft 41 is cut with a moderate space 111, near gear 91. (See Figure 14.) 101 represents a square end of shaft 41, between this space 111 and 91, for square slide 102. Worm 42 is fitted on the near end of shaft 41 by 111. 103 is a continuation of 102 which has an internal spiral gear of similar pitch to that of 42, whose teeth mesh into teeth 42 with reasonable working clearance and is lubricated. Both 102—103 are bisected in two pieces which are fitted on and fastened by six bolts. Flange 105 is a perpendicular extension of 102—103 with two bearing surfaces against each side of which are thrust ball bearings 106. These bearings are assembled by entrance between gap 111 where rod 41 is cut. Then the two parts 102—103 are slipped through the holes in the bearing, which latter are brought against 105. Double clamps 107 hold them in position by four bolts, two of which hold the fingers 108, which are connected with control rod 109.

It is evident that as gear 91 rotates the front end of shaft 41 will likewise rotate part 102—103. As the two parts of shaft 41 are held in position by thrust bearings 110 their only possible movement is rotation. As 102 is of a square joint it must rotate and its rear extension 103 must rotate with the front or left part of 41. The internal worm gear 103 accordingly locks the external worm gear 42 which it encases and rotates the rear end of shaft 41.

However, when control rod 109 pulls or pushes fingers 108 on thrust bearings 106, flange 105 moves 102—103 either forward or backward as it is on a lubricated sliding joint. This movement forces a rotating movement in a direction that depends on the forward or backward motion of 103. Thus when shaft 41 is rotating it will either rotate slightly faster in relation to the crankshaft when 102—103 is moved horizontally, or by the reverse action, slightly slower. Thus by moving control lever 109, the relative position of the worm gear 42, as to gear teeth 7 of sleeve valve 3, is changed so that the slide valve is either advanced or retarded, at the desired position control lever 21 is locked. This latter control contrivance 5 is seen in position on Figure 11.

50 I request that Letters Patent be granted on the following claims:

1. In an internal combustion engine, a cylinder with means supplying a charge of low-grade explosive mixture thereto, an aligned coaxial chamber with means to supply and ignite a charge of high-grade mixture therein, and rotary sleeve means with a single port controlling admission of the ignited mixture into and discharge of the ignited mixture from said chamber into the engine cylinder for ignition of the charge in the latter.

2. In an internal combustion engine, a cylinder with means supplying a charge of low-grade explosive mixture thereto, an aligned coaxial chamber with means to supply and ignite a charge of high grade explosive mixture therein, and rotary sleeve means with a port controlling discharge to and admission of the explosive mixture from said chamber into the engine cylinder for igniting the charge in the latter, said sleeve means having its auxiliary port for scavenging remote from and in a different plane to the port aforesaid.

3. In an internal combustion engine, a cylinder with means supplying a charge of low-grade explosive mixture thereto, an aligned coaxial cham-

ber with means to supply and ignite a charge of high-grade mixture therein, and rotary sleeve means with port control admission of the explosive mixture into and discharge of the ignited mixture from said chamber into the engine cylinder for ignition of the charge in the latter, and means to angularly advance the rotary sleeve up to approximately 120 degrees relative to the engine crank-shaft so as to change the positions of the ports therein relative to corresponding ones in the chamber wall.

4. In an internal combustion engine, a cylinder with means supplying a charge of low-grade explosive mixture thereto, an aligned coaxial chamber with means to supply and ignite a charge of high-grade mixture therein, rotary sleeve means with port control of admission of the explosive mixture into and discharge of the ignited mixture from said chamber into the engine cylinder for ignition of the charge in the latter, and means to advance or retard the rotary sleeve means in the chamber to regulate the time of ignition of the mixture in the engine cylinder.

5. In an internal combustion engine, a cylinder with means supplying a charge of low-grade atomized fuel mixture, and aligned coaxial chamber with means to supply and ignite a charge of high grade explosive gas, means for variably shifting said chamber about its axis within an angle of approximately 120 degrees to control the timing of ignition in said chamber, a sleeve in the chamber having a perimetrically toothed solid base and a single port in its cylindrical wall to control admission and exhaust of the explosive gas to and from said chamber for ignition of the low grade atomized fuel mixture, and means for continuously rotating the sleeve aforesaid in a predetermined direction.

6. In an internal combustion engine, a cylinder with means supplying a charge of low-grade atomized fuel mixture, an aligned coaxial chamber with means to supply and ignite a charge of high-grade explosive gas, parallel link mechanism for variably shifting said chamber about its axis within an angle of approximately 120 degrees to control the timing of ignition in said chamber, a sleeve in the chamber having a perimetrically toothed solid base and a single port in its cylindrical wall to control admission and exhaust of the explosive gas to and from said chamber for ignition of the low grade atomized fuel mixture, and means for continuously rotating the sleeve aforesaid in a predetermined direction.

7. In an internal combustion engine, a cylinder with means supplying a charge of low-grade atomized fuel mixture, a substantially-smaller aligned coaxial chamber with means to supply and ignite a charge of high-grade explosive gas, means for varying the time of ignition in said cylinder, a sleeve valve in such chamber with means whereby it is rotatable continuously in one direction, and means including a two-part shaft with associated mechanism whereby said parts may be moved axially towards or away from one another to effect annular shifting of the sleeve valve within the coaxial chamber for controlling admission and exhaust of the high-pressure gas for ignition of the low-grade atomized fuel mixture.

8. In an internal combustion engine, a cylinder with means supplying a charge of low-grade atomized fuel mixture, an aligned coaxial chamber with means to supply and ignite a charge of high-grade explosive gas, means for variably

- shifting said chamber about its axis within an angle of approximately 120 degrees to control the timing of ignition in said chamber, a sleeve in the chamber having a perimetrical toothed solid base and a single port in its cylindrical wall to control admission and exhaust of the explosive gas to and from said chamber for ignition of the low grade atomized fuel mixture and means for continuously rotating the sleeve aforesaid in a predetermined direction.

9. In an internal combustion engine, a series of cylinders with common means supplying charges of low-grade atomized fuel mixture, a substantially-smaller aligned coaxial chamber above each cylinder with means to supply and ignite the charges of high-grade explosive gas, means for varying the time of ignition in said chambers, a sleeve valve in each chamber with common means whereby they are rotatable continuously in one direction, and means including a two-part shaft with associated mechanism whereby said parts may be moved axially towards or away from one another to effect annular shifting of the sleeve valves relative to the associated coaxial chambers for controlling admission and exhaust of the high-grade gas for ignition of the low-grade atomized fuel mixture.

10. In an internal combustion engine, a cylinder with means supplying a charge of low-grade atomized fuel mixture, a substantially-smaller aligned coaxial chamber with means to supply and ignite a charge of high-grade explosive gas, means for varying the time of ignition in said chamber, a sleeve valve in such chamber with means whereby it is rotatable continuously in one direction, and means including a two-part shaft with associated mechanism whereby said parts may be moved axially towards or away from one another to effect annular shifting of the sleeve valve relative to the coaxial chamber for controlling admission and exhaust of the high-grade gas for ignition of the low grade atomized fuel mixture.

11. In an internal combustion engine, a cylinder with means supplying a charge of low grade atomized fuel mixture, an aligned coaxial chamber with means to supply and ignite a charge of high-grade explosive gas, means for varying the time of ignition in said chamber, a sleeve valve in such chamber with means whereby it is rotatable continuously in one direction, means including a two-part shaft with associated mechanism whereby said parts may be moved axially towards or away from one another to effect annular shifting of the sleeve valve relative to the coaxial chamber for controlling admission and exhaust of the high-grade gas for increased compression and ignition of the low grade atomized fuel mixture.

12. In an internal combustion engine, a cylinder with means supplying a charge of low-grade atomized fuel mixture, an aligned coaxial chamber with means to supply and ignite a charge of high-grade explosive gas, means for variably shifting said chamber about its axis within an angle of approximately 120 degrees to control the timing of ignition in said chamber, a sleeve in the chamber having a perimetrical toothed enlarged solid base and a single port in its cylindrical wall to control admission and exhaust of the explosive gas to and from said chamber for increased compression during ignition of the low grade atomized fuel mixture and means for continuously rotating the sleeve aforesaid in a predetermined direction.

13. In an internal combustion engine, a series of cylinders with a manifold supplying charges of low-grade atomized fuel mixture thereto, a substantially-smaller aligned coaxial chamber above each cylinder with means to supply and ignite a charge of high-grade explosive gas, means for varying the time of ignition in said chambers, a sleeve valve in each chamber with means whereby it is rotatable continuously in one direction, and mechanism whereby said valves may be angularly moved relative to the axial chamber for controlling admission and exhaust of the high-grade gas for increased compression during ignition and ignition of the low grade atomized fuel mixture, and means for reducing the volume not swept through by the piston following ignition.

14. In an internal combustion engine, a series of cylinders with a manifold for supplying charges of low-grade atomized fuel mixture, an aligned coaxial chamber above each cylinder with means to supply and ignite a charge of high-grade explosive gas, means for variably shifting said chamber about its axis within an angle of approximately 120 degrees to control the timing of ignition in said chambers, a sleeve in each chamber having a perimetrical toothed enlarged solid base and a single port in its cylindrical wall to control admission and exhaust of the explosive gas to and from said chambers for ignition of the low grade atomized fuel mixture, and means for increasing compression in piston chamber by explosion from primary chamber at time of ignition, followed by closing of primary chamber at predetermined time and means coordinating and continuously rotating the sleeves aforesaid in a predetermined direction.

15. In an internal combustion engine, a series of cylinders with manifold means for supplying charges of low-grade atomized fuel mixture to the respective cylinders, a substantially-smaller aligned coaxial chamber above each cylinder with means to supply and ignite a charge of high-grade explosive gas, means for varying the time of ignition in said chambers, a sleeve valve in each chamber with means whereby they are coordinatively rotatable continuously in one direction, and means including a two-part shaft with associated mechanism whereby said parts may be moved axially towards or away from one another to effect angular shifting of the sleeve valves relative to the axial chambers for controlling admission and exhaust of the high-grade gas for ignition of the low grade atomized fuel mixture and increased compression and burning mixture with above means for timing, and closing the port to primary chamber to limit clearance volume above piston during the expansion of said low grade charge.

16. In an internal combustion engine, a series of cylinders with manifold means for supplying charges of low-grade atomized fuel mixture to the respective cylinders, an aligned coaxial chamber above each cylinder with means to supply and ignite a charge of high-grade explosive gas, means for coordinatively shifting said chambers about their axes within an angle of approximately 120 degrees to control the timing of ignition in said chambers, a sleeve in each chamber having a perimetrical toothed enlarged solid base and a single port in its cylindrical wall to control admission and exhaust of the explosive gas to and from said chamber for ignition of the low grade atomized fuel mixture and for increasing power by additional burning gases and in-

- creased compression prior to complete combustion of low grade gas and common means for continuously rotating the sleeves aforesaid in a predetermined direction.
- 5 17. In an internal combustion engine, a series of cylinders with manifold means for supply charges of low-grade atomized fuel mixture to the respective cylinders, a substantially smaller aligned coaxial chamber above each cylinder with means to supply and ignite a charge of high-grade explosive gas, means for concurrently varying the time of ignition in said chambers, a sleeve
- 10

valve in each chamber, and means whereby they are coordinatively-rotatable continuously in one direction, said means including a two-part shaft with associated mechanism whereby said parts may be moved axially towards or away from one another to effect angular shifting of the sleeve valves relative to the axial chambers for controlling admission and exhaust of the high-grade gas for ignition of the low-grade atomized fuel mixture.
